Primary Examiner — Zenia Bennett(74) *Attorney, Agent, or Firm* — McDonnell Boehnen Hulbert & Berghoff LLP(57) **CLAIM**

The ornamental design for an LED lighting fixture, as shown and described.

DESCRIPTION

FIG. 1 is a perspective top view of an LED lighting fixture having the inventive design;

FIG. 2 is a perspective bottom view of the LED lighting fixture shown in FIG. 1;

FIG. 3 is a left side view of the LED lighting fixture shown in FIG. 1;

FIG. 4 is a right side view of the LED lighting fixture shown in FIG. 1;

FIG. 5 is a front view of the LED lighting fixture shown in FIG. 1;

FIG. 6 is a back view of the LED lighting fixture shown in FIG. 1;

FIG. 7 is a top view of the LED lighting fixture shown in FIG. 1; and,

FIG. 8 is a bottom view of the LED lighting fixture shown in FIG. 1.
